DESIGN FOR AN ELECTRIC LAMP

Hans T. Scheidacker, Brooklyn, N. Y., assignor to
Davart Incorporated, New York, N. Y., a corporation of New York

Application July 20, 1940, Serial No. 93,801

Term of patent 3½ years

To all whom it may concern:

Be it known that Hans T. Scheidacker, a citizen of Germany and resident of Brooklyn, in the county of Kings and State of New York, has invented a new, original, and ornamental Design for an Electric Lamp, of which the following is a specification, reference being had to the accompanying drawing, forming part thereof, in which,

Fig. 1 is a front elevational view of a lamp embodying my new design; and

Fig. 2 is a side elevational view thereof.

The dominant features of my design reside in the portions shown in full lines.

I claim:

The ornamental design for an electric lamp, substantially as shown and described.

HANS T. SCHEIDACKER.
